COPY HOLDER FOR TYPEWRITERS AND OFFICE MACHINES

Filed Oct. 5, 1936

UNITED STATES PATENT OFFICE

2,128,304

COPY HOLDER FOR TYPEWRITERS
AND OFFICE MACHINES

Paul Kobler, Lynbrook, N. Y.

Application October 5, 1936, Serial No. 104,089

5 Claims. (Cl. 120—28)

My invention relates to improvements in copyholders, particularly in new means for holding a sheet or number of sheets of manuscript or other writing, while being copied from by a typewriter operator whereby time and labor are saved and mistakes avoided.

My invention will be understood by reference to the accompanying drawing, where the same parts are indicated by the same numerals 10 throughout the several views.

Fig. 1 is a perspective view of the copyholder with the paper holding members.

Fig. 2 is an enlarged side view of the paper holding member with attached weight.

Fig. 3 is an enlarged side view of the paper holding member without attached weight.

The copyholder shows the application of fingers 1 and 2 held in position by a support.

The fingers 1 and 2 are constructed preferably 20 with a rod. This rod or finger has at its end a rubber 10 which prevents the paper from slipping out underneath the finger.

Fingers 1 and 2 together with their supporting means 3 and 4 can be moved from "A"—"B" 25 or "C"—"D" respectively. Parts 3 and 4 are bent forward at 11. The supporting means with fingers (paper holding clips) 1 and 2 slide from "A" to "B" and from "C" to "D" on bar 14. This bar 14 is through a rod 15 so constructed that the 30 two ends "A" and "C" can hardly bend and will always remain in a very straight line. This is necessary so that the supporting means 3 and 4 can easily slide from "A" to "B" and "C" to "D".

The same construction of bar 14 with rod 15 is 35 repeated with bar 16 and rod 17. Bar 16 forms a part of the copyholder plate 18 and is reinforced by rod 17.

The paper holding clips 1 and 2 are kept in position by the weight of the rod 12 which at 40 one end is bent (32 and 33) to make this rod heavier and at the same time holding it from flapping over backwards. The bent parts 32 and 33 are so long that they touch bar 14 when folded upwards.

45 The paperholding rod 12 with its finger pieces 1 and 2 is pivoted in its support 11.

The finger pieces 1 and 2 of rod 12 touches the copyplate or bar 16 above the pivoted point.

This upward inclination of the finger pieces 50 1 and 2 is the most important part of the paperholding clip. A rubber attached over each finger piece will hold any paper tight to the copyplate or bar 16. The upward inclination of the finger pieces 1 and 2 which can be seen especially well 55 in Figs. 2 and 3 has the advantage that the fin-

ger pieces will open by itself if a paper is pushed underneath. No extra movement or lifting of the paperholding clip is necessary. On the other hand, once the paper is under the paperholding clips they can not be pulled down anymore. As 5 said before the support of the paperholding clip is bent out at 11 so that there is an eccentric action on the rubber piece of the finger and bar 16 on the copyplate.

When pulling the paper downward from underneath the fingers 1 and 2 the supports 11 would bend outwards and the eccentric action of the fingers would be lost if the supports 11 would not be held in position by the flat piece 14, over which the supports slide. Further describing the paperholding clip and its mounting on the support, it is quite important that the finger parts 1 and 2 with the rubber pieces are standing out, away from the supports 11. This allows the paper, placed on the copyholder plate to go far under the fingers 1 and 2 and allows also to pull the paper on the copyplate to any height desired.

Bar 12 of the paperholding clip can not slide out of support 11 as on one side of support 11 the paperholding clip is bent backwards and on the other side bar 12 has a pin to prevent any sliding out of support 11.

The main feature of support 11 is that this support is not pivoted on bar 14. On the contrary the flat side of bar 14 prevents support 11 from bending outwards so that the rubbers on fingers 1 and 2 get a very strong eccentric action on the copyplate. The more the paper is pulled downward from underneath the rubber fingers 1 and 2 the more the eccentric action of these fingers 35 hold the paper tight on its place.

The operation of my device is as follows:

An unusually large sheet is placed on copyplate 18. Fingers 1 and 2 with their supporting means are so designed that they can take care of unusual paper sizes. The finger supporting means 11 slide for this purpose from "B" to "A" and from "D" to "C".

The position of fingers 1 and 2 shown in Fig. 1 is ready for the largest sheet. But the smallest 45 sheet can be taken care of, if we slide the fingers 1 and 2 towards "B" and "D" together with their supporting means 11.

These fingers 1 and 2 work like eccentric levers, as shown in Fig. 2 and Fig. 3. At the end, where 50 they touch the copyplate they are provided with a rubber 10.

These fingers 1 and 2 hold in their position by their own weight.

For single small sheets the weight of the small 55

finger itself is sufficient and if a special copyholder for small work would be needed, such a finger could be made out of a straight piece of rod or bar and could be pivoted at its opposite end, as shown in Fig. 3. For heavier papers or bunch of papers the weight of the fingers 1 and 2 has to be heavier. Bar 12 forming at one end fingers 1 and 2 is therefore bent at the other end, preferably backwards in such a way, that the weight of fingers 1 and 2 is increased. At the same time this backward bent part No. 32 and 33 in Fig. 1 and 32 in Fig. 2 holds the fingers 1 or 2 from turning all the way over, when a piece of paper is pushed under the rubber parts.

With other words the fingers 1 and 2 are by their own weight steadily pressed against the copyplate or bar 16 in Fig. 1. It is possible to slide one or several papers at a time under a finger, but it is impossible to pull the papers back. Herein is the greatest advantage. The papers may be pulled upwards. In any position the fingers are always ready to hold the paper tight. The papers may also be taken out sideways very easily. But the more the paper pulls downwards the more the fingers will hold it. Therefore to take away a paper from underneath a finger you have to lift the finger by hand, or pull the paper away sideways or upwards.

It is important to know that the fingers are set away from the support, so that there is space provided for the paper, in case the paper is drawn upwards.

The object of my invention is to use the eccentric levers or fingers with the supporting means at different points of the copyplate and that the fingers with their supporting means embody a new paperholding clip which opens by itself as soon as paper is pushed underneath the paperholding clip.

Now the operator can hold the paper with both hands and place it under the paperholding clip much better, quicker and more accurately.

Having thus described my invention, what I claim and desire to secure by Letters Patent of the United States is:

1. In a copyholder, a copy support, and means for holding a copy thereon, comprising paper holding clips and its mounting on the support, said paper holding clips being constructed in the form of a lever which has its turning point underneath the end of said lever which touches

the copy or the copyplate and said turning point being at a certain distance away from the copyplate so that the copy can easily be pushed underneath said lever, which being so constructed has an eccentric action whereby the copy holds 5 tight on the copyplate and cannot be pulled downwards, but easily upwards and sideways, said paper holding clips work under their own weight and are opened simply by pushing the copy underneath without being operated by 10 hand.

2. In a copyholder, a copy support, and means for holding a copy thereon, comprising paper holding clips and its mounting on the support, said paperholding clips being constructed in the 15 form of eccentric levers which have the point touching the copyplate at a certain distance away from the copyplate so that the copy can easily be pushed underneath said levers but also at a certain distance away from its mounting so that 20 the copy can be drawn upwards as much as desired.

3. In a copyholder, a copy support and means for holding a copy thereon, comprising paper holding clips and its mounting on the support, 25 said paperholding clips being constructed in the form of eccentric levers, which are continued in a horizontal part, this part being bent backwards again, so as to give additional weight to the eccentric lever.

4. In a copyholder, a copy support and means for holding a copy thereon, comprising paper holding clips and its mounting on the support, said paperholding clips being constructed in the 35 form of eccentric levers, which are continued in a horizontal part, this part being bent backwards again, so as to prevent the eccentric lever from falling forwards, at the same time giving additional weight to the eccentric lever.

5. In a copyholder, a copy support and means 40 for holding a copy thereon, comprising paper holding clips and its mounting on the support, these supports being held in position by a flat piece of metal on which flat piece the supports slide in and outwards, these supports being provided with means to hold the paperholding clips with their eccentric action underneath and sufficiently above the point where the paperholding clips touch the paper on the copyplate.

PAUL KOBLER.
